UNITED STATES PATENT OFFICE.

JOHN E. ERICKSON, OF ST. PAUL, MINNESOTA, ASSIGNOR TO ANDERSEN LUMBER COMPANY, OF BAYPOET, MINNESOTA, A CORPORATION OF WISCONSIN.

DADO-FORMING MACHINE.

Application filed October 19, 1925. Serial No. 63,318.

In the manufacture of window frames of the mullion or double window type, it has been customary to cut parallel grooves, mortises or dadoes in the upper surface of 5 the sill near the middle portion thereof, to receive the lower ends of adjacent window jambs. These grooves or dadoes extend only partially across the sill and are therefore blind, and the tool in cutting or forming them, leaves a beveled or inclined surface at the inner ends and this has been 10 cut out manually by a chisel or other suitable tool to form a square shoulder or vertical face at the inner ends of the dadoes 15 against which the edges of the jambs will be snugly seated to form a tight substantially weather-proof joint. Two operations have heretofore been necessary in forming the 20 grooves, one to cut them to the required depth, using a suitable machine, and the other a hand operation to provide a square shoulder at the inner end of each blind groove.

The object of my invention is to provide 25 a machine in which, by a single operation, the sill grooves or dadoes may be cut, and a square shoulder formed at the inner ends thereof with the same operation, thereby effecting a considerable saving in time and 30 dispensing with the usual manual operation.

Other objects of the invention will appear from the following detailed description.

The invention consists generally in various constructions and combinations all as 35 hereinafter described and particularly pointed out in the claims.

In the accompanying drawings forming 40 part of this specification,

Figure 1 is a vertical transverse sectional view through a dadoing machine embodying my invention.

Figure 2 is a detail view partially in section of the upper portion of the machine 45 showing the movable jaw in its unlocked or open position;

Figure 3 is a plan view of the machine;

Figure 4 is a detail sectional view showing the adjustable feature of the machine 50 for increasing or decreasing the distance between the dadoes;

Figure 5 is a vertical sectional view show-

ing the manner of mounting the dado-cutting knives;

Figure 6 is a detail view partially in section of the knife holder showing the means for aligning the dado-cutting knives therein;

Figure 7 is a sectional view on the line 7—7 of Figure 6;

Figure 7^a is a detail sectional view on the line 7^a—7^a of Figure 6;

Figure 8 is a perspective view of one of the knives by means of which the dado or groove is cut;

Figure 9 is a perspective view of a mullion window sill showing the position of the dadoes therein;

Figure 10 is a transverse sectional view of the sill showing the dado therein and the 70 square shoulder or face at the inner end thereof.

In the drawing, 2 represents the base of the machine and 3 upright standards thereon. 4 is a drive shaft journaled in suitable 75 bearings in the upper rear portions of said standards. This shaft projects outwardly beyond the bearings at each end and one end is provided with a suitable driving pulley 5. A yoke 6 has arms 7 journaled on the 80 projecting ends of the shaft 4 and adapted to oscillate vertically thereon. A series of eccentrics 8, 9, 10 and 11 are mounted on the shaft 4, the eccentrics 8 and 9 being splined thereon by means of the feather or key 12 85 while the eccentrics 10 and 11 are secured to the shaft. Suitable eccentric straps 13 are provided for each eccentric and arms 14, 15, 16 and 17 extend forwardly from said eccentric straps beneath the yoke 6. A slide 18 is 90 mounted on the yoke 6 to move longitudinally thereon, and a screw 19 is mounted in bearings in a housing 20 on the yoke 6 and has an operating wheel 21. This screw is held against longitudinal movement in its 95 bearing by the hub of the operating wheel on one side of the bearing and a collar 22 secured to the shank of said screw on the opposite side of the bearing. The threaded portion of the screw engages a block or lug 100 23 on the slide 18 so that revolution of the screw will operate to feed the slide back and forth on the yoke 6 across the machine. The slide has an arm 24 thereon supporting a

horizontal guide 25 and a similar arm 24^a on the housing 20 supports a guide 25^a. Slides 26 are mounted on the guides 25 and 25^a to move freely forwardly and backwardly thereon, and the rear portions of these slides are pivotally connected with the forward ends of the arms 14 and 17 so that when the eccentrics are revolved the slides 26 will be reciprocated on their supporting guides in a horizontal direction. A carrier plate 27 is mounted on each slide and secured thereto adjustably by suitable means such as set screws 28. Upon loosening these screws the carrier plates and slides can be relatively adjusted to the desired position.

29 is a bracket seated against the face of each carrier plate 27 and adjustable thereon vertically and horizontally by means of adjusting screws or bolts 30 and 31. This manner of mounting the brackets 29 allows for universal adjustment of the groups of knives. Each knife bracket 29 is provided with a series of sockets 32 arranged at an incline therein and adapted to receive the shanks of a corresponding number of knives 33 and 34. The knife 33 has an angled upper end 35 terminating in a transverse cutting edge 33^a and provided with oppositely arranged cutting edges 36 spaced apart a distance corresponding to the desired width of the groove or dado. The knives 34 terminate at their upper ends in similar cutting edges 36^a and cooperate with the knife 33 to cut the fibers of wood transversely and form the dado as the knife bracket is reciprocated.

The knives are adjustable vertically in their sockets by suitable means such as set screws 37 engaging the lower ends of the knife shanks and operating to force them upwardly within their sockets or seats until the desired relative adjustment is obtained, it being of course desirable that the knives should be on substantially the same level as regards their cutting edges in order that the dadoes or grooves may be cut a uniform depth. Plates 38 are secured to the faces of the brackets by suitable means such as bolts 39 and by the adjustment of these bolts, the knives when properly aligned may be rigidly secured. Such mounting also allows the convenient removal of the knives from the brackets whenever desired. These knives, in the operation of the machine, have a reciprocating movement forwardly and backwardly and operate somewhat similar to a saw, engaging the wood surface and cutting the dadoes therein to the required depth while held in working position by the operator.

60 The transverse cutting edge 33^a of the knife 33 will pass between the fibers of the wood the width of the groove or dado while the edges 36 at right angles substantially to the edge 33^a will sever the fibers on both sides of the groove and form the side walls 65 thereof. The cutting edges 36^a of the knives

34 will follow after the edges 36 and complete the cut cooperating with the edges 36 until the proper depth of the groove or dado is reached. It is important in a tool of this kind that the knives cut the walls of the 70 grooves squarely and cleanly without chipping or splintering the surface of the sill around the grooves and hence the arrangement of the knives and their manner of operation is important in a machine of this 75 kind. It has been found by experience that provision must be made for disposing of the chips cut by the knives and prevent the knives from clogging. I, therefore, provide recesses 33^b between the adjacent knives and 80 grooves 33^c extending downwardly in the walls of the supporting brackets 29 to allow the convenient discharge of the chips and waste from the cutting edges of the knives.

Relatively shorter knives 60 having vertical cutting edges 60^a are also mounted in the brackets 29 adjacent the knives 33, (see Figures 5, 6, 7 and 8). These knives function to cut away a portion of the raised portion 52^a which is usually provided at the 90 inner edge of the sill as shown in Figure 10. The cutting edges of the knives 60 are arranged at a relatively lower level than the cutting edges of the knives 33 and 34 so that when the grooves or dadoes have been 95 cut the required depth, a portion of the raised strip 52^a will be removed adjacent the outer edge of each groove to provide a seat for the window jambs. It is to be understood that the lower ends of the jambs are 100 usually provided with tongues adapted to be fitted into the grooves, and it is therefore desirable to cut away a portion of the raised surface 52^a to allow the jambs to be seated snugly against the sill.

105 The arms 15 and 16 operated by the eccentrics on the shaft 4 are mounted to slide in bars 41 which are pivotally supported at 42 on the arms 24 and 24^a. The forward ends of the bars 41 have knives 43 demountably secured therein with their transverse cutting edges on a level substantially with the cutting edges 36 of the knives 33 and 34 when raised, and positioned to move vertically and cut a square face or shoulder at the inner ends of the dadoes or grooves in the sill so that when the work is completed these grooves or dadoes will have the appearance substantially as shown in Figure 10, and of sufficient depth to receive the ends of the jambs, the square shoulders at the inner ends of the dadoes against which the jambs abut effectually closing and concealing the joint and protecting the grooves in the sill 115 from the weather.

120 The adjustment of the screw 19 will have the effect of moving the arms 14 and 15, and the knives carried thereby, back and forth on the shaft 14 to increase or decrease the distance between these arms and the corre- 130

sponding arms 16 and 17 and properly space the knives to obtain the desired distance between the dadoes.

The shaft 4 being revolved and the arms reciprocated by the action of the eccentrics, provision is made for raising the knives into contact with the under surface of the sill. For this purpose, I prefer to provide a treadle or foot lever 40 pivoted at 44 on the base and having an adjustable pivoted connection with a cross bar 45 on the slides 26. The effect of depressing the lever 40, therefore, will be to raise the slides and the knives to a level where, upon reciprocation of these knives through the revolution of the shaft 4, the grooves or dadoes will be cut in the sill and the ends of such grooves squared or faced by the operation of the knives 43. The depth of the dadoes will depend of course upon the degree of elevation of the knives and this can be regulated by the operator through a screw 46 mounted in the treadle 40 and positioned to engage the base and limit downward movement of the treadle and consequently vertical movement of the slides and the cutting knives.

As the arms, slides and their attachments will have considerable weight, I prefer to counterbalance them by means of a lever 47 pivoted at 48 on the base and having an adjustable weight 49 at one end, and a pivoted link connection 50 at its other end with the inner end of the treadle 40. By means of this counterbalance, the operator can adjust the mechanism so that the treadle can be depressed with comparatively little effort. As the feed of the knives to the work is determined by the depression of the treadle, it is evident that the operator of the machine will familiarize himself with the work so that he will raise the knives to cut the dadoes gradually, feeding them upwardly as they cut into the wood and as the knives are held to the work by the pressure of the foot on the treadle, it is evident that the operator, at any time, can allow the knives to drop down away from the work or can instantly terminate the dado-cutting operation as soon as the knives have reached the required depth of cut.

As will appear from the foregoing description, the knives 33 and 34 will have a horizontal reciprocating movement by the action of the eccentrics while the knives 43 through the vertical oscillation of the bar 41 actuated by the eccentrics will have a vertical movement to cut square faces or shoulders at the ends of the dadoes, but without having any horizontal reciprocating movement therein. Therefore, when the operator depresses the treadle, the groups of knives will be raised and the revolution of the eccentrics will reciprocate the groove-cutting knives 33 and 34, which have been raised into engagement with the sill by the action

of the treadle and at the same time, the knives 43 will be raised to cut across the grooves or dadoes at the inner ends thereof and form square faces or shoulders at this point.

At the forward portion of the frame, I provide a fixed jaw 51 wherein one edge of the sill 52 is seated. A movable jaw 53 has brackets 54 thereon to engage the other edge of the sill and clamp it firmly against the fixed jaw. The movable jaw is mounted to swing upon links 55 pivoted to the frame of the machine, and an oscillating movement is imparted to said movable jaw by means of links 56 which connect it pivotally with crank arms 57 mounted upon a rock shaft 58 having suitable bearings in the frame of the machine and provided with an operating handle 59.

In preparing to use the machine, the operator will place the sill to be grooved between the movable jaws, operate the shaft 58 to firmly clamp the sill between the jaws, and having firmly secured the sill in the proper position, will depress the lever 40 and raise the reciprocating cutters or knives into engagement with the under side of the sill. The reciprocation of the knives, due to the action of the eccentrics on the shaft 13, will cut the grooves in the sill, and the recesses in the shoulder at the inner edge of the sill, the feed depending upon the pressure of the foot of the operator upon the lever 40. After a little experience the machine attendant will become expert in the operation of this lever and will be able to feed the knives so that the grooves will be cut smoothly in the surface of the sill without chipping or splintering. At the same time that the knives are reciprocated, an oscillating movement will be imparted to the knives 43 through the bars 41 and the cutting edges of these knives will cooperate with the knives 33 and remove the corners at the inner ends of the grooves and provide square shoulders or faces at this point to receive the ends of the window jambs. Thus, the grooves may be formed neatly and expeditiously and with one operation and the usual labor of cutting out the corners or squaring the faces of the inner ends of the grooves by hand is entirely eliminated. The distance between the grooves or dadoes is easily regulated by the lateral adjustment of the eccentrics on the shaft 4 as described, and the depth of the cut can, of course, be regulated by the degree of movement of the foot lever 40. Thus the machine can be adapted for sills or window frames of different length and thickness.

I claim as my invention:

1. A device of the class described including a work support, a knife supported for reciprocation at a level below the support, and adapted to swing upwardly to operative

position, a second knife supported to engage the work at the end of the cut, crosswise thereof, and means for synchronizing the movements of the supports, and causing the 5 first mentioned knife to plane and the second knife to chop at the end of the cut.

2. In combination a work support tool slides reciprocably mounted beneath the support and adapted to be swung toward and 10 away from the work during reciprocation, a tool carrier supported upon the slide having a series of tools spaced in direction of reciprocation of the carrier and each having a pair of transversely opposed and spaced 15 knives, corresponding knives aligned in direction of reciprocation and each tool having a planing edge, transverse in respect to the first mentioned knives, second tool supports rockably mounted, said supports each having 20 a tool to engage at the endmost portion of the cut in advance of the first mentioned tools, and means for moving and for synchronizing the movements of the supports, to obtain planing and chopping movements, 25 of respective tools.

3. In combination a work support, a tool slide reciprocably mounted beneath the support and adapted to swing toward and away from the work during reciprocation, a tool 30 carrier supported upon the slide and having groove cutting knives therein, and a second tool carrier rockably mounted and having a tool to engage at the endmost portion of the 35 cut in advance of the first mentioned tools, and means for moving and synchronizing the movements of the supports to obtain planing and chipping movements of respective tools.

4. A block having lateral grooves in one 40 face, a knife in each groove having a transverse cutting edge and longitudinal scoring edges one at each opposite side, the edges of all knives aligned in direction of the cutting movement, a plate laterally engaging the knives to clamp them in the 45 grooves, said block being grooved transversely between each knife with the groove leading laterally in a direction away from the cutting edges to one of the lateral surfaces of the block.

5. A block having knives arranged in pairs, the members of which abut, one pair in advance of the other, each knife having a transverse cutting edge, and one member of each 55 pair having in addition longitudinal scoring edges one at each opposite side aligned in direction of cutting movement, and the other member of each pair having a single longitudinal scoring edge disposed at that 60 side remote from the companion knife, said edges being also aligned in direction of cutting movement, the cutting edges of those knives which have the single scoring edge lying in a plane inwardly from the cutting 65 edges of the companion knives.

6. A block having knives arranged in pairs, one pair in advance of the other, each knife having a transverse cutting edge, and one member of each pair having in addition longitudinal scoring edges one at each opposite side aligned in direction of cutting movement, and the other member of each pair having a single longitudinal scoring edge disposed at that side remote from the companion knife, said 75 edges being also aligned in direction of cutting movement, the cutting edges of those knives which have the single scoring edge lying in a plane inwardly from the cutting edges of the companion knives. 80

7. A block having grooves extending inwardly from one face, knives arranged in the grooves in pairs the members of which laterally abut, one pair in advance of the other, each knife having a transverse cutting 85 edge and one member of each pair having in addition longitudinal scoring edges one at each opposite side aligned in direction of cutting movement and the other member of each pair having a single longitudinal scoring edge disposed at that side remote from the companion knife, said edges being also aligned in direction of cutting movement, the cutting edges of those knives which have the single scoring edges, lying in a plane inwardly from the cutting edges of the companion knives, and a plate clamping laterally engaging one member of each pair to secure the pairs in the grooves. 90

8. A block having a series of inclined 100 parallel grooves, a pair of knives abuttingly arranged in each groove, one pair in advance of the other, each knife having a transverse cutting edge and one member of each pair having in addition longitudinal scoring 105 edges one at each opposite side aligned in direction of the cutting movement and the other member of each pair having a single longitudinal scoring edge disposed at that side remote from the companion knife, said edges being also aligned in direction of cutting movement, the cutting edges of those knives which have the single scoring edge lying in a plane inwardly from the cutting edges of the companion knives, and a plate 110 clamping laterally engaging one member of each pair to secure the pairs within the grooves, said block being grooved transversely between each pair of knives, with the 115 grooves leading laterally in a direction away from the cutting edges to one of the lateral surfaces of the block.

9. A block having inclined grooves, a pair of knives abuttingly arranged in each groove, one pair in advance of the other, each knife having a transverse cutting edge and one member of each pair having in addition longitudinal outwardly convex scoring edges one at each opposite side aligned in direction of the cutting movement and 120

the other member of each pair having a single longitudinal outwardly convex scoring edge disposed at that side remote from the companion knife, said edges being also aligned in direction of cutting movement, the cutting edges of those knives which have the single scoring edge lying in a plane in-

wardly from the cutting edges of the companion knives, and a plate clampingly engaging one member of each pair to secure 10 the knives within the grooves.

In witness whereof, I have hereunto set my hand this 15th day of October, 1925.

JOHN E. ERICKSON.
